Patented Nov. 23, 1976

242,493

DISPOSABLE SYRINGE FOR FLUID DELIVERY APPARATUS

Stephen H. O'Leary, San Diego, Calif., assignor to
IVAC Corporation, San Diego, Calif.

Filed Sept. 26, 1974, Ser. No. 509,558

Term of patent 14 years

Int. Cl. D24—02

U.S. Cl. D83—12 A

Fig. 1

Fig. 2

Fig. 3

Fig. 5

FIG. 1 is a front perspective view of a disposable syringe for fluid delivery apparatus embodying my new design;

FIG. 2 is a left side elevational view thereof;

FIG. 3 is a top plan view thereof;

FIG. 4 is a bottom plan view thereof; and

FIG. 5 is an inverted, front perspective view thereof with the piston in fully extended condition.

I claim:

The ornamental design for a disposable syringe for fluid delivery apparatus, as shown.
